UNITED STATES PATENT OFFICE.

THADDEUS HYATT, OF NEW YORK, N. Y., ASSIGNOR TO ELIZABETH ADELAIDE LAKE HYATT, OF SAME PLACE.

ILLUMINATING GRATING OR VAULT-COVER.

SPECIFICATION forming part of Letters Patent No. 257,713, dated May 9, 1882.

Application filed April 11, 1882. (No model.)

To all whom it may concern:

Be it known that I, THADDEUS HYATT, of the city, county, and State of New York, and a citizen of the United States, have invented 5 certain new and useful Improvements in Illuminating-Gratings and Vault-Covers, of which the following is a specification.

Like letters refer to like parts in all the figures of the drawings attached hereto and making part of this specification.

The object of my improvement is to guarantee a perpetually safe foot-surface to that class of vault-covers and illuminating-gratings known to the trade by the name of "knob-lights," the safety of which as a foot-surface to be walked upon in the public streets depends upon "knobs" or "protuberances" of metal made upon the face of the grating between the glasses. These lights, so long as 15 the knobs remain, may be walked upon with safety; but when worn off the metal becomes polished and dangerous and the addition of fresh knobs a source of expense and trouble.

Figure 1 represents in cross-section a knob-light of the ordinary construction. A A is the iron grating; B B, the glasses; a a, the knobs or iron protuberances.

Fig. 2 represents the same after the knobs and glasses have been worn down. a' a' represent the iron surface now polished and dangerous.

Fig. 3 represents in plan the improved knob-light. A is the iron grating; B, the glasses; a, the iron knobs, and b b a filling of concrete 35 or artificial stone, which surrounds not only the glasses but also the knobs.

Fig. 4 is a cross-section of Fig. 3 on the line x x.

Fig. 5 is a cross-section representing the 40 improved knob-light when worn smooth.

My invention is a concrete knob-light, the glasses being surrounded by a body of hydrau-

lic cement, concrete, or artificial stone, above the face of which rise the metal knobs to protect the curved faces or lens form of the glasses, 45 the combination of lens-shaped glasses with such knobs and body of concrete forming a part of my invention.

The mode of making these improved concrete lights is substantially the same as the 50 manufacture of ordinary concrete lights, except that my improved lights are molded face downward-on-account of the knobs, for which purpose I employ a mold-board or facing-plate as the bottom of the mold which is made with 55 indents or holes to let the knobs sink into to the depth they are required to stand above the level of the concrete when the work is completed; also, I prefer to make the mold-board with cores to form the light-holes in the body 60 of concrete, so as to set the glasses after the concrete has turned to stone.

What I claim as my invention, and desire to secure by Letters Patent, is—

1. An improved "concrete light" made by 65 combining lens-shaped glasses with concrete and protecting metallic knobs, substantially as and for the purposes herein set forth and illustrated.

2. An improved concrete light made by combining protecting metallic knobs with the concrete and glasses, substantially as and for the purposes herein set forth and illustrated.

3. An improved "knob-light" made by combining with the glasses and knobs a non-slip- 75 ping or foot-holding material which practically surrounds both glasses and knobs, substantially as and for the purposes herein set forth and illustrated.

THADDEUS HYATT.
